UNITED STATES PATENT OFFICE.

CHARLIE CARTER AND SOLOMON MILLER, OF BONE GAP, ILLINOIS.

BLOCK-MOLD.

986,266.

Specification of Letters Patent. Patented Mar. 7, 1911.

Application filed June 6, 1910. Serial No. 565,207.

To all whom it may concern:

Be it known that we, CHARLIE CARTER and SOLOMON MILLER, citizens of the United States, residing at Bone Gap, in the county 5 of Edwards and State of Illinois, have invented certain new and useful Improvements in Block-Molds, of which the following is a specification.

Our present invention relates to block 10 molds of the expanding and separable type, our object being to provide a simple and inexpensive construction in which to mold tapering blocks, and one which will be strong and durable and wherein the parts may be 15 readily and quickly replaced, the principal use of which blocks is to form foundation stones for frame buildings, such as barns, granaries, corn-cribs and the like, under which the blocks are placed vertically with 20 their larger ends set into the supporting surface.

With this in mind, our invention resides in the features of construction set forth in the accompanying drawing, in which,

25 Figure 1 is a side elevation of the assembled mold, Fig. 2 is a plan view thereof, Fig. 3 is a longitudinal section therethrough, Fig. 4 is a transverse vertical section therethrough, taken on line 4—4 of Fig. 1, and Fig. 5 is 30 an enlarged detail of a fragment of one of the sides.

Referring to these figures, the base 10, of the mold, has equi-distantly spaced bearing blocks 11 upon its under surface, and secured 35 thereto transversely thereof, the ends of said blocks having U-shaped members 12 secured thereto. The sides 13, of the mold, have vertical bars 14 secured upon their outer surface to coincide with the members 12, the 40 lower ends of said bars being tapered and bent outwardly to form locks 15 which engage the U-shaped members 12 when the lower edges of the sides 13 are placed in position along the longitudinal edges of the 45 base 10. The inner faces of the sides 13 are provided with transversely alined pairs of

downwardly converging angle bars 16, to receive, thereagainst, the partition plates 17 extending between the sides 13 and which are tapered in accordance with the flare of 50 the sides as shown. The upper edges of the sides 13 are provided with a plurality of slots 18, these slots being located at the ends of the sides and between each pair of angle bars 16, and being adapted to receive therein 55 the connecting bars 19 which extend through the sides 13 and have transverse pieces 20 at one end and have their opposite ends apertured to receive locking pins or keys 21, connected loosely thereto by chains 22. These 60 bars 19, being rigid, thus serve to connect the upper edges of the sides 13 without interfering with the mold spaces, that is, the spaces between the partition plates 17 of 65 each pair. The parts thus formed may be 70 readily and quickly placed together and taken apart, and the connecting members of the sides and base, while strong and lasting, may be readily removed when damaged, and others put in their place.

We claim:

The combination of a base, upwardly extending and outwardly flaring sides, relatively engageable means carried by said base and sides to connect the lower edges of the 75 latter upon the sides of the former, angle bars secured in alined, downwardly converging pairs upon the inner surfaces of said sides, partition plates disposed against said bars, said sides having slots in their upper 80 edges at their ends and between each pair of said angle bars, and connecting members extending through the said slots, having means to engage the outer surfaces of the sides to prevent the same from spreading. 85

In testimony whereof we affix our signatures in presence of two witnesses.

CHARLIE CARTER.
SOLOMON MILLER.
